(54) **LOOM, WEAVING, FIGURED GOODS**

(76) Inventor: **John Smith**

John Smith, of Shafferslawn, State of Pennsylvania
Letters Patent.

The schedule referred to in this Letter Patent and making part of the same, containing a description in the words of the said John Smith himself of his improvement in the loom for weaving figured work,

To all whom it may concern.

Be it known that I, John Smith of Shafferslawn in the County of Lebanon & State of Pennsylvania, have invented certain improvements in the loom for weaving figured work, which improvement appertain principally to that part of the loom which operates upon the draw-boys and their appendages which are connected in forming the pattern to be woven. In the figure loom commonly employed, there are pins in a cylinder, which as the cylinder is turned, operates upon the shifters, and forces them back, a mode of procedure which produces considerable resistance in working of the loom, and in damp weather not unfrequently causes the pins to break or produce other inconveniences.

By my improvement the shifters are drawn back by means of a treadle connected with an upper treadle or lever acting like that which lifts the draw-boys. This lever stands in a line with the draw-boy lever, and when it is drawn down by a lever a friction roller attached to it is brought into contact with a latch on the upper end of a vertical lever, the lower end of which is fixed in a roller or shaft which carries the frame work, and turns upon guides. This vertical lever is forced back by the friction roller, and is so connected with the shifters as to draw them back with it, and whilst at the same time the cylinder is turned to the proper distance in a way to be presently described. When this is effected the latch, the latch from its con-

construction, disengage itself from the friction roller and the vertical lever is forced forward into its place by a spring, thus causing the shiftings to return to their places and draw between the pins on the cylinder.

The Drawing deposited in the Patent office, will more distinctly show the arrangement of this and other parts of the apparatus than they can be made known in words only. The same lever which carries the friction roller is made to turn the cylinder. It has for this purpose a shaft or band fastened to its inner end, which passes round a pulley, by the action of which a lever is raised, which is so connected as to push the foot-hands or pall, that operates on ratchet-teeth on the end of the cylinder in the usual way, and I adapt the same loom to the weaving of fine work, such as carpet, or of coarse work such as carpet, by shifting the yoke, which operate upon the draw-boys, for this purpose I employ the double draw-boy, somewhat similar to that used in the double carpet-loom, but different from it in causing it to work either of two sets of gear, but only one at the same time, whilst in that calculated for double work, both sets of draw-boys are worked together whilst I use only one set upon the same work, shifting them as may be necessary, my loom not being calculated for double work.

What I claim as my invention, is the arrangement of that part of the loom first described, by which the shiftings are drawn instead of being forced back by the action of the pins upon the cylinder, and this I claim whether the effect be produced precisely in the manner represented or in any other which is substantially the same, I also claim the mode of connecting the lever which draws the shifting back, by which the cylinder is turned at the proper time & to the proper distance.

I claim likewise the employment of the two sets of gears in the same loom, in the manner described by which it is adapted either to coarse or fine work. It is to be understood that I do not intend to claim the individual parts connected in

United States Patent

Patent No.: X8797

in either of these operations, but only that general arrangement
and connection of these parts by which new and useful effects are
produced.
